GARMENT IRONING MACHINE HAVING A BOTTOM PAD AND A HEATED METAL COVER

Elbert H. Posey, Nurnberg, Germany

Application June 25, 1953, Serial No. 364,058

6 Claims. (Cl. 38—21)

The invention relates to garment ironing machines having an oscillating yoke which is provided with a heated metal cover and which is pressed down against a pad mounted on the supporting frame at working level, whereby the ironing of the garment put on the pad will be done within a certain time for pressing down. The operation is by hand or by means of a treadle, but it can be also actuated by power drive.

Ironing the garment by such devices is done within a certain time. However, thereby it is possible to iron only a single garment, for instance, trousers, or shirts, unless there is sufficient place to put the garments side by side.

This invention has for its purpose to improve the method of working and to reduce considerably the ironing time of each garment. This is accomplished by employing an intermediate member accommodated within the path of travel of the cover, the cover being connected with or by it in an oscillating manner. It is also provided with a pad and a heating body, the latter of which is directed toward the bottom pad and the former toward the metal cover. This intermediate member can be oscillated about the same shaft as the top metal cover and its heated (bottom) metal body is supplied from its steam piping by means of flexible connections.

The accompanying drawing shows by way of example one embodiment of the invention in which

Fig. 1 is a side elevation, and

Fig. 2 is a front elevation of a garment ironing machine. The usual supporting frame 1 with its two lateral cheeks is fitted at working level with the bearing plate 2 having a bottom pad 3 fixed thereon provided with a projecting and supporting leg 4. The rearward portion of the supporting frame 1 extends to two split bearings 5 in which a shaft 6 carrying the ironing yoke 7 is arranged. The latter oscillates about the shaft 6, being provided with a handle 8 on its exterior end for this purpose. Besides this handle 8 it is possible to actuate also a treadle 9.

The oscillating yoke 7 is provided with an adjustably mounted heating body at its bottom surface having a slightly concave shape which is brought to rest closely on the pad surface, when the oscillating yoke 7 is operated. The heating body comprises a metal cover 10 provided with flexible supply and return pipes 12 and 13, which are connected to corresponding pipings. The yoke 7 is equipped also with springs which return it to the open position according to Figs. 1 and 2 after releasing the handle 8 or the treadle.

Within the space between the bottom pad 3 and the metal cover 10 there is accommodated a further oscillating member 14 which is covered on its top surface with a pad 15. The latter is provided on its bottom surface with a suitable hollow sheet body 16 which is connected with the common heating system by means of pipings 17 and 18. The intermediate member 14 is carried by oscillating levers 19 being arranged on both sides of the bearings 5 on the end portions of the shaft 6. Counter-levers 20 of these oscillating levers serve to connect suitable retracting springs 21.

2
A second pressing surface is obtained for garment by the described intermediate member 14, the pad 15 of which registers with the camber of the metal cover 10 and its heating body 16 with the bottom pad 3. This pressing surface is operated by a common drive. As soon as the handle 8 is pressed down, the cover first engages the pad 15 and then on its further path of travel presses down the intermediate member 14 so that the heated metal body 16 of the latter rests on the bottom pad 3 and the smooth ironing of the garment thereon takes place. Upon releasing the handle 8, after an engagement time of two or three minutes, the parts return automatically, owing to the springs, to the positions shown in Fig. 1 which are limited reasonably by suitable stops.

In such a manner it is possible to iron twice the number of garments with the same engagement and, as the times for putting on the garment remain the same, no loss of time occurs and the success of the time for ironing is reduced by one half will be fully maintained.

It is preferable to provide a recess on the front edge of the intermediate member in order to allow a well shaped top pressing surface, for instance, in case of ironing trousers, so that the legs can be put on in a very smooth manner.

The object of the invention can be used both for new ironing devices and already existing ironing machines, with which it is possible to be installed by using the described intermediate member 14.

What I claim to secure by Letters Patent is:

1. In a garment ironing machine having a bottom pad and a heated oscillating cover, the improvement comprising an intermediate member mounted to oscillate with said cover, a pad on the upper surface of said intermediate member, a heating body on the surface of said intermediate member directed toward the bottom pad, and means for applying force in one and the same direction to first press the cover against the pad on the intermediate member and to subsequently press the intermediate member against the bottom pad.

40 2. In a machine according to claim 1, including retracting spring means connected to said cover and to said intermediate member to raise the latter from the bottom pad upon release of the applying force.

45 3. An ironing machine comprising first pressing means mounted for turning movement about an axis, a first heating body on a surface of said first pressing means, said first heating body providing a first pressing surface, second pressing means mounted for rotative movement in the same direction as the first pressing means, said second pressing means being provided with a second pressing surface which faces the first pressing surface, said second pressing means being also provided with a second heating body on a face opposite said second pressing surface, means providing a stationary pressing surface facing the second heating body, and means for exerting application of force in one and the same direction to press the first heating body initially against said second pressing surface and thereafter to press said first heating body together with said second pressing surface and through the latter the second heating body against the stationary pressing surface.

4. The apparatus of claim 3, in which the first and second pressing means are mounted to turn on a common horizontal axis, and further including oscillating lever means pivoted upon said axis and supporting said second pressing means upon said axis, and spring means attached to said oscillating lever means to retract the second pressing means from the stationary pressing surface.

5. The apparatus of claim 3, in which the first and second pressing means are mounted to turn on a common horizontal axis and said direction of application of the pressing force is downward.

6. An ironing machine comprising first pressing means mounted for rotative movement on a horizontal axis, a first heating body on a surface of said first means, said heating body providing a first pressing surface, second pressing means mounted for turning movement on a horizontal axis, said second pressing means providing a second pressing surface facing the first pressing surface and providing a second heating body on an opposite face of said second pressing means, means providing a stationary pressing surface facing the second heating body, 10 means for applying force without altering the direction thereof to press the first pressing means against the second

pressing means and the second pressing means against the stationary pressing surface, and means for automatically causing the second pressing means to rise upon release of the force applied to the first pressing means.
